UNITED STATES PATENT OFFICE.

GEORGE VOLNAGEL, OF BREMERTON, WASHINGTON.

MAKING MOLDS FOR SHOE-LASTS.

1,027,016.

Specification of Letters Patent. Patented May 21, 1912.

Application filed November 28, 1911. Serial No. 662,811.

To all whom it may concern:

Be it known that I, GEORGE VOLNAGEL, a citizen of the United States, residing at Bremerton, in the county of Kitsap and 5 State of Washington, have invented new and useful Improvements in Making Molds for Shoe-Lasts, of which the following is a specification.

My invention relates to means for forming molds for molding shoe lasts.

My device provides means adapted to be inserted over the person's foot and inserted into a molding substance whereby when said foot is withdrawn heated metal may be 15 allowed to run into the opening formed thereby, and harden, thereby forming a shoe last.

My device further provides means adapted to be inserted over a person's foot 20 and inserted into a molding substance whereby an opening is formed to conform with the outer surface of the person's foot. When the foot is withdrawn, heated metal may be introduced into said opening and 25 allowed to harden. The last that is formed from the metal after it has hardened, will conform with the shape of the person's foot whereby a shoe may be made upon said last, as this will be obvious from here- 30 inafter disclosure.

With the foregoing and other objects in view, my invention relates to such details of construction and in the arrangement and combination of parts as will be herein- 35 after fully described and pointed out in the appended claims.

In describing my invention in detail reference will be had to the accompanying drawings wherein like characters denote 40 like or corresponding parts throughout the several views, and in which:—

Figure 1 is a side elevation of my invention. Fig. 2 is a front elevation of the same. Fig. 3 is a perspective view of a mold casing. Fig. 4 is a front elevation of my invention, showing the same disposed within a molding substance. Fig. 5 is a fragmentary view of the mold casing. Fig. 6 is a 45 perspective view of a section of the mold casing substance after my invention has been withdrawn therefrom.

In the accompanying drawings which illustrate the preferred form of my invention the numeral 1 designates the stocking 50 formed of sections of elastic material which are secured together as shown, to form a

fin 2. I do not limit myself to the specific means for securing the sections together, however they being preferably fused. It is now obvious that by providing an elastic 60 stocking and elastic fin, different sizes of feet may be inserted into the stocking without distorting the fin.

I provide a mold casing 3 which is made in sections the purpose of which will be 65 hereinafter fully described and specifically set forth in the appended claims.

In the operation of my device I dispose within the mold casing 3, a molding substance of any desired type as shown at 4. 70 A person's foot is then inserted into the elastic stocking 1 and inserted into the molding substance 4. The substance is then allowed to harden and the casing withdrawn from the same. It will be readily 75 seen that the fin 2 serves to separate the molding substance into two parts, whereby the foot may be easily withdrawn. The two sections of the molding substance may then be secured together by simple means 80 (not shown) and heated metal let run into the opening formed by the elastic stocking whereby a shoe last may be formed. It will be appreciated that the last thus formed will be slightly smaller than the person's 85 foot, this occurring from the width of the fin 2. It is my object to make the last slightly smaller because of the fact that the shoe formed upon the said last will fit the person's foot more readily than one 90 which is formed upon a last the exact size of the person's foot.

It will be readily seen from the foregoing that when a shoe is made upon the last the interior thereof will conform with the 95 shape of the person's foot that was inserted into the elastic stocking 1 whereby persons can have their shoes made in this manner.

It is thought from the foregoing that the advantages and novel features of my invention will be appreciated.

Having thus fully described my invention, what I claim as new and desire to secure by Letters Patent is:—

1. In a device of the character described, 105 an elastic stocking to be received by a person's foot, a fin carried by said stocking said stocking and fin to be inserted into a molding substance for the purpose described.

2. In a device of the character described, 110 an elastic stocking to be received by a per-

son's foot, a fin carried by said stocking and extending from back and bottom thereof said fin and stocking to be inserted into a molding substance for the purpose described.

3. In a device of the character described, an elastic stocking having a fin secured thereto, the said fin extending from the front, back and bottom thereof, said stock-

ing to receive a person's foot, said stocking to be inserted into a molding substance, said fin adapted to separate said substance into parts as described.

GEORGE VOLNAGEL.
